D. Nicholson,
Sawing Shingles,

No 27,192.

Patented Feb. 14, 1860.

UNITED STATES PATENT OFFICE

DAVID NICHOLSON, OF LOCKPORT, NEW YORK, ASSIGNOR TO HIMSELF AND CHARLES R. FOX, OF SAME PLACE.

METHOD OF FEEDING THE BOLT TO THE KNIFE IN SHINGLE-MACHINES.

Specification of Letters Patent No. 27,192, dated February 14, 1860.

To all whom it may concern:

Be it known that I, DAVID NICHOLSON, of Lockport, in the county of Niagara and State of New York, have invented a new and Improved Machine for Sawing Shingles, Headings for Casks, and Like Articles; and I do hereby declare that the following is a full, clear, and exact description of the same, reference being had to the annexed 10 drawings, making a part of this specification, in which—

Figures 1 and 2, are side elevations of my invention, one side view being opposite to that of the other. In both views the lower 15 part of the framing is bisected. Fig. 3, is a horizontal section of ditto, taken in the line α , α , Fig. 1. Fig. 4, is a detached sectional view of a portion of the friction device connected with the feed mechanism. 20 Fig. 5, is a detached face view of the slides connected with the bolt-adjusting mechanism, the machine being bisected as indicated by the line z , z , Fig. 1, and the eye looking in the direction indicated by the arrow. 25 Fig. 6, is a detached face view of one of the slides which actuate the racks connected with the dog bar. Fig. 7, is a horizontal section of ditto, taken in the line α' , α' , Fig. 6. Fig. 8, is a vertical section of ditto, taken 30 in the line y' , y' , Fig. 6.

Similar letters of reference indicate corresponding parts in the several figures.

The object of this invention is to obtain a machine by which shingles may be sawed 35 from the bolt in proper taper-form, and the taper varied as may be required, the machine also admitting of "stuff" being sawed with parallel sides, such as is used for the heading of casks, and other, or similar, 40 purposes.

To enable those skilled in the art to fully understand and construct my invention I will proceed to describe it.

A, represents a rectangular frame formed 45 of longitudinal bars a , connected by traverse bars b . Two of the bars a , a , have ways c , on their upper surfaces for a carriage B, on which the bolt C, shown in red outside, is secured. To each side of the frame 50 A, an upright bar D, is attached, the upper ends of which are curved or bent in a horizontal position and sustain the bearings d , of a horizontal shaft E, on one end of which a circular saw F, is secured. On the

shaft E, there is a cone of pulleys e , around 55 which a belt f , passes, said belt also passing around a cone of pulleys g , on a shaft G, placed transversely in the frame A. In the frame A, there are two shafts, one H, besides the one G, just referred to. The two 60 shafts G, H, are parallel with each other and they are connected at one end by gear wheels h , h . On each shaft G, H, a conical head I, is secured, said heads fitting in sockets J, which are placed loosely on the shafts, 65 see Fig. 4. Each socket J, has a pinion i , secured to its outer side and concentrically with it. K, is a lever which is secured to the frame A, by a fulcrum pin j . This lever is connected by pins k , with the heads I, I, 70 and by actuating this lever either head I, may be forced into its socket J, so as to cause the same to rotate with its shaft G, or H. The fulcrum pin j , it will be seen by referring to Fig. 3, is between the two shafts 75 G, H, and consequently when one socket J, is connected with its shaft the other is detached from its shaft, for when one head is forced into its socket the other is moved out from its socket. The lever K, has a 80 vertical pin l , attached to it—the use of which will be presently shown.

To one end of the frame A, a vertical bar L, is attached. In the inner side of this bar two slides M, N, are placed. These 85 slides are connected by links m , m , to a lever O, the fulcrum of which is midway between the two links, see more particularly Fig. 5. Each slide M, N, has a vertical slot n , made through it and similar slots o , o , are made 90 through the bar L, the slots o , being directly in front of the slides M, N, so that the slots in the bar and those in the slides may register or coincide with each other by an adjustment of the slides. The lower slide 95 N, is connected to a lever O, the fulcrum of which is at p , and the inner end of the lever O, has a diamond-shaped projection q , attached, the use of which will be presently explained.

The carriage B, is provided with rollers r , which work on the ways c , c , and to the under side of the carriage a longitudinal rack P, is secured, which rack gears into the pinions i , i , of the sockets J, J, on the shafts 105 G, H. To the bottom of the carriage B, there is also attached a projection s , having two oblique sides which act against the

pin l , of the lever K , as will be hereinafter more particularly described. On the carriage B , two traverse bars t, t , are placed, one above the other in an inclined plane, 5 as shown clearly in Fig. 2. The bars t, t , form guides for a bar Q , which is fitted on them at right angles and allowed to slide freely thereon. To the bar Q , the dogs u, u , are attached and between which 10 the bolt C , is secured.

To each end of the dog bar Q , a double rack R , is secured. These racks may be termed double as each is formed of two longitudinal parts v, w , connected by a dove-tail joint a' , and allowed to slide freely one over the other. The parts v, w , are adjusted by a screw b' , as shown clearly in 15 Fig. 8. The teeth of the two parts v, w , of the racks have their front parts beveled at one side as shown clearly in Fig. 7, and the teeth of one part v , are placed in a reverse position to those of the other, as shown clearly in Fig. 7, the teeth of the lower part w , of the rack being shown by 20 dotted lines. The racks R, R , pass transversely through horizontal slides S, T . These slides are fitted in proper guides c' , attached to the inner side of the carriage B , and each side is provided with two projecting bars d', e' , which work between the teeth of the parts v, w , of the rack and actuate them. This will be fully understood by referring to Figs. 7 and 8. The lower side T , is connected to a vertical shaft 25 s' , which has a crank g' , at its lower end, and the two slides S, T , are connected by a lever U .

The operation is as follows: The bolt C , is secured between the dogs u, u , and as the 40 dog bar Q , has an inclined position the bolt C , will also have an inclined position relatively with the saw F , as shown clearly in Figs. 1 and 2. The carriage B , has its rollers r , fitted on the ways c, c , and the two parts v, w , of each rack R , are adjusted so that the teeth of the two parts will be a proper distance apart one with the other, corresponding to the thickness of the butts and points of the shingles. Motion is given the 45 shaft E , by any convenient power and the carriage B , and consequently the bolt is fed toward the saw, the head I , of the shaft H , being forced into the socket J , of said shaft. When the bolt is fed toward the saw for 50 the purpose of sawing shingles it has an oblique position given it in order that the shingles may be sawed in taper form and this oblique position is given the bolt in consequence of the slides S, T , actuating the 55 racks R, R . After the saw F , has completed its cut, the projection s , on the carriage strikes a pin l' , of lever K , and actuates said lever so that the head I , of shaft G , will be forced in its socket and the head of shaft H , 60 withdrawn or loosened in its socket. This

movement of lever K , therefore reverses the movement of the carriage and the latter is gigged back. As the latter reaches the termination of its backward movement, the lower slide T , will strike the lower slide N , in the 70 bar L , that is to say, provided the upper slide S , was brought in contact with the upper slide M , in the bar L , at the previous backward movement of the carriage when the slide T , strikes the slide N , the end of 75 the upper slide S , will pass through the slots n, o , in the slide M , and bar L , as said slots are then in register, or, coincide with each other, and when the upper slide S , strikes the slide M , the end of the lower slide T , 80 will pass through the slots n, o , in the slide N , and bar L , as the latter slots will then be in register. Thus it will be seen that the two racks R, R , are alternately actuated and the position of the slotted slides M, N , are 85 changed each time the carriage B , moves forward, in consequence of the crank K, g' , striking the projection g , of lever O . The bars d', e' , of the slides S, T , as before stated, pass between the teeth of the parts 90 v, w , of the racks to actuate them, and when the uppermost rack is actuated to give the taper for the butt of the shingle, the lowermost one is actuated to form the point, and vice versa. In case heading for barrels are 95 to be sawed, the two parts v, w , of each rack are adjusted with their teeth in line with each other, or the teeth of one part v , are made to coincide with those of the other so that each rack will be moved an equal distance corresponding to the spaces between the teeth and the "stuff" sawed of a corresponding thickness. When the carriage 100 nearly reaches the termination of its backward movement the projection s , strikes the pin l , of lever K , and thereby reverses the movement of the carriage so that it will again move forward toward the saw. It will be seen therefore that by the peculiar construction of the racks the "stuff" may 105 be sawed in taper form as for shingles or sawed in pieces of equal thickness for heading for casks and like purposes. It will also be seen that the machine is rendered automatic in its action throughout. By having 110 the bolt C , inclined relatively with the saw as shown, a smooth clean cut is insured and the saw not liable to be deflected from its proper cutting plane.

In consequence of the traverse bars t, t , 115 being placed on the carriage B , in an inclined plane as shown in Fig. 2, and previously referred to, the bar Q , which is fitted thereon will consequently be inclined and also the bolt C . This inclined position of the bolt, shown in Figs. 1 and 2, causes the saw to act upon it in a direction obliquely with its fiber, or grain which, it will be understood runs longitudinally with the bolt. If the bolt were presented endwise to the 120

125 130

saw as usual, the bolt in this case being in a horizontal position, the saw would have a tendency to follow the grain of the wood and be deflected from its proper cutting plane, precisely the same as a knife in riving shingles from a bolt will follow the grain of the wood. When however the saw acts upon the bolt in a direction obliquely with its fiber as is the case when the bolt is presented to the saw in an inclined position, this tendency is avoided and the saw instead of following the grain of the wood will cut it, in fact the shingle or slab will be sawed from the bolt without any splitting or riving action. Another advantage attending the presenting of the bolt to the saw in an inclined position, is, that the saw will not have a tendency to run off from the body or main portion of the bolt a contingency which frequently occurs in the sawing of thin stuff, owing to the slight resistance which a thin

slab offers to an outward lateral movement of the saw.

Having thus described my invention what I claim as new and desire to secure by Letters Patent, is—

1. Constructing the racks R, R, of two toothed longitudinal parts v, w, so arranged as to be capable of adjustment, one with the other, for the purpose of varying the taper of the shingles, and sawing stuff of equal thickness throughout when desired.

2. The arrangement of the racks R, R, slides S, T, connected by the lever V, and the slotted slides M, N, operated by the lever O, and crank g', and fitted in the bar L, substantially as shown for the purpose of actuating the racks R, R.

DAVID NICHOLSON.
